(57) **CLAIM**

The ornamental design for an instrument for treatment of soft tissue, as shown and described.

DESCRIPTION

FIG. 1 is a front perspective view of an instrument for treatment of soft tissue showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is an enlarged partial front view of the left end thereof;

FIG. 9 is an enlarged partial front view of the right end thereof;

FIG. 10 is an enlarged left elevation view thereof; and,

FIG. 11 is an enlarged right elevation view thereof.

The dashed broken lines shown in FIGS. 1-11, the dashed-dotted broken lines shown in FIGS. 1-3 and 6-9, and the dotted broken lines shown in FIGS. 4, 5, 10, and 11 are included for the purpose of illustrating environmental subject matter only and form no part of the claimed design. The surface shading between alternating pairs of straight dashed broken lines on the end portions of the instrument up to the dashed-dotted broken lines indicate claimed surfaces, whereas the remaining portions of the end portions of the instrument are unclaimed.
